UNITED STATES PATENT OFFICE

PETER PETREKE, OF PHILADELPHIA, PENNSYLVANIA

NECKTIE FASTENER

Application filed June 15, 1928. Serial No. 285,656.

My invention relates to new and useful improvements in a necktie fastener and one of its objects is to provide an exceedingly simple and effective device of this character which forms a part of a made-up or manufactured necktie in contra-distinction to those where the user may tie different ties thereon.

Another object of my invention is to provide a necktie fastener constructed from spring wire and fashioned to provide a pair of wings, each consisting of two wire strands spaced apart and one of the strands of each wing forming a part of a button loop which will be maintained upon a collar button because of the resiliency between the two strands of each wing.

A further object of the invention is to provide a necktie fastener consisting of the wire or metal form enclosed within a stock except for the button loop, said fastener adapted to be suitably connected with a preconstructed necktie.

A still further object of the invention is to provide a necktie fastener, which, when in use, will not only positively hold the tie in place, but will also maintain the collar in a proper closed position.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:

Fig. 1 is an isometric view of a collar and necktie illustrating an application of my invention.

Fig. 2 is a similar view of a collar and the wire or metal form or frame with a portion of the collar broken away to plainly show the manner in which the form or frame attaches to the collar to the button.

Fig. 3 is a front elevation of another form of tie showing the fastener connected therewith.

Fig. 4 is a perspective view of the wire or metal form or frame.

Fig. 5 is a top plan view thereof.

Fig. 6 is a side elevation of the same.

Fig. 7 is a front elevation of the complete fastener showing the form dotted within the stock.

Fig. 8 is an enlarged sectional view on the line 8—8 of Fig. 7.

In carrying out my invention as herein embodied, particular reference being had to Figs. 4 to 6 inclusive, 10 represents the form or frame constructed from suitable spring metal, preferably wire, so fashioned as to provide a pair of diverging wings 11, each wing including two strands 12 and 13 spaced from each other with the forward portions of the strands 13 terminating short of the adjacent forward portions of the strands 12, said strands 13 being joined by an arcuate portion 14.

The forward portions of the strands 12 are bent downward and then upward into to inverted U to form the button loop 15, and because of the resiliency between the two strands 13, which might be termed the upper section of the fastener, and the two strands 12, which might be termed the lower section of the fastener, the loop 15 will be held in positive engagement with a collar button when the device is in use as plainly shown in Fig. 2.

The wings are enclosed within a stock 16 which is of suitable textile fabric but the button loop 15 is uncovered or projects through an opening in the stock as will be obvious by reference to Fig. 7.

A pre-constructed necktie 17 such as shown in Fig. 1 and generally known as a four-in-hand may be secured to the fastener by sewing the same to the front portion of the stock while the wing portions may be covered, at least the front faces thereof with portions of the same material as the necktie to represent the neck band of said necktie, or a bow necktie 18, Fig. 3, may be attached to the fastener by sewing it to the front portion and then covering the outer faces of the wings with the same kind of material as that from which the necktie is made.

In Figs. 1 and 2, I have shown a turned down collar 19, with which a necktie including my improved fastener is used and as will be obvious by reference particularly to Fig. 2, when the necktie is to be placed in the collar or removed therefrom, the wings of the fastener are projected between the inner or outer panels of the collar and by forcing the lower portion of the fastener including the two strands 12 of the frame toward the upper portion of the frame, the loop may be passed over the button 20, but when in engagement with said button, the resiliency of the wing elements will absolutely prevent accidental displacement of the loop from the button.

Because of the upwardly and rearwardly extending formation of the wings, the tips thereof engage the inside of the fold of the collar at separated points on either side of the collar button and therefore act upon the collar on angular lines with, I might say, the collar button as a fulcrum, thus tending to elevate the sides of the collar until the front edges are brought snugly together at the top as plainly shown in Fig. 1, and therefore the collar will always be maintained in proper form for neat appearance.

Of course I do not wish to be limited to the exact details of construction as herein shown, as these may be varied within the limits of the appended claims without departing from the spirit of my invention.

Having thus fully described my invention, what I claim as new and useful is:—

1. A necktie fastener formed from a piece of wire bent up to produce a button loop open at the lower end and including two substantially vertical spaced strands, said strands being bent back upon themselves and projected to points in the region of the top of said button loop and then extended rearwardly and slightly upwardly to provide lower portions of wings, and then curved and extended forwardly in spaced substantially parallel relation to the lower portions of the wings to form the upper portions of said wings and finally terminating at a point slightly to the rear of and above the button loop where they meet.

2. The structure set forth in claim 1 in combination with a stock of textile material completely covering all of the structure except the button loop.

55 In testimony whereof, I have hereunto affixed my signature.

PETER PETREKE.
